UNITED STATES PATENT OFFICE.

EDWARD CHARLES HAWKINS, OF ALLEGHENY, PENNSYLVANIA, ASSIGNOR TO
SKELOTREE COMPANY, A CORPORATION OF NEW YORK.

DEVICE FOR SHAPING SHOES.

990,866.

Specification of Letters Patent.

Patented May 2, 1911.

Application filed December 15, 1909. Serial No. 533,219.

To all whom it may concern:

Be it known that I, EDWARD CHARLES HAWKINS, a citizen of the United States, and a resident of Allegheny, in the county 5 of Allegheny and State of Pennsylvania, have invented certain new and useful Improvements in a Device for Shaping Shoes, of which the following is a specification.

The present invention has reference, generally, to improvements in devices for retaining boots, shoes, and the like in their proper form and shape when the same are removed from the feet of the wearer.

This invention has for its primary object 15 to provide a simple, neat and cheaply constructed device for retaining boots, shoes and the like in their proper form and shape, whereby the same are prevented from becoming distorted, cracked or wrinkled as so 20 frequently happens when the said boots, shoes and the like are removed and left to stand in a wet or even slightly damp condition.

A further object of the present invention 25 is to provide a device of the character and for the purposes above set forth, which will accomplish all the objects and functions of the ordinary wooden shoe-tree, but which obviates the principal objection of said shoe-trees, namely, the lack of a proper ventilation and drying of the shoe, because the said shoe-tree fills up the interior of the boot, shoe or the like, thereby preventing a proper 30 circulation of air therein. The present invention being adapted to be arranged upon the exterior of the shoe permits the air to enter into and circulate within the same.

A still further object of this invention is to provide a means for adjusting or regulating the spring-tension of my present shoe reforming and shaping device.

Other objects of the present invention not at this time more particularly enumerated will be clearly understood from the following detailed description of my present invention.

With the various objects of my present invention in view, the same consists in the novel construction of shoe reforming and shaping device hereinafter set forth, and, furthermore, said invention consists in the novel arrangements and combinations of the various parts, as well as in the details of the

construction of the same, all of which will be hereinafter more fully described, and 55 then finally embodied in the clauses of the claim.

The invention is clearly illustrated in the accompanying drawings, in which:—

Figure 1 is a side elevation of the sole of a 60 shoe showing the present invention arranged in operative connection therewith, the dotted line showing the shape of the shoe before my novel device is applied thereto, the full lines showing the normal and proper form 65 and shape to which the shoe is brought and held by my novel device. Fig. 2 is a bottom plan view of a shoe with my novel device operatively arranged therewith. Fig. 3 is a perspective view of my novel device re- 70 moved from a shoe.

Similar characters of reference are employed in all of the above described views to indicate corresponding parts.

Referring now to the said drawings the 75 reference character 1 indicates the complete device, embodying the principles of my present invention, the same comprising a form of spring steel wire, the same being doubled upon itself to form a pair of spring arms 2 80 and 2'. The said spring arms 2 and 2' are each provided at or near their middle portions with outwardly bent or looped portions 3 and 3'. The said spring arms 2 and 2' are further provided at their inner ends 85 with outwardly flaring portions 4 and 4', the ends of said flaring portions 4 and 4' being bent upwardly to form upwardly extending portions 5 and 5', and integrally connected with the free ends of said portions 90 5 and 5' are inwardly projecting sole-clips 6 and 6'. The outer ends of said spring-arms 2 and 2' are each provided with upwardly bent portions forming the upwardly extending arms 7 and 7', and integrally connected with the free ends thereof is an inwardly extending loop portion 8, the same providing a toe-clip. The normal tendency 95 of said spring arms 2 and 2' is to spring away from each other, and in order to increase or decrease the spring tension of said spring-arms 2 and 2' in their action upon the shoe there is provided a tubular runner-member 9—slidably arranged upon said spring-arms between the bent or looped portions 100 3 and 3' and said toe-clip 8. Said 105

runner-member 9 is provided with a face-plate 10, the same being adapted to receive upon its face any desirable advertising matter.

5 The method of applying and using my novel device is as follows:—The toe-clip 8 is arranged to engage the toe-portion of the sole of the shoe, then the sole 11 of the shoe is bent downwardly until it assumes a normal flat position, the spring-arms 2 and 2' are then spread apart so that the sole-clips 6 and 6' are caused to respectively engage the opposite sides of the sole 11 at 2 near the instep portion thereof. The rise of the 15 sole 11 at the arch 12 places a tension upon the spring-arms 2 and 2', this tension tends to retain the sole 11 and consequently the upper of the shoe in a proper form and shape. The tension of the said spring-arms 20 2 and 2' may be increased or decreased by sliding said runner-member 9 away from or toward the toe-clip 8; and the said runner-member 9 has the further function of causing a more stable holding engagement 25 of said sole-clips 6 and 6' with the sole 11, thus eliminating the liability of said reforming and shaping device from being acciden-

tally removed from its operative engagement with the boot, shoe, or the like.

I claim:—

A device for re-forming and shaping shoes, comprising a toe-clip, a pair of rearwardly extending spring-arms connected with said toe-clip, said spring-arms being provided with integral bent or looped portions and outwardly flaring ends, sole-clips integrally connected with the free ends of said spring-arms, a tubular runner slidably arranged conjointly upon said spring-arms forward of said bent or looped portions said tubular runner being adapted to be moved backward or forward with relation to said toe-clip to draw said spring-arms together laterally and to also increase or decrease the spring leverage of said spring-arms, substantially as and for the purposes set forth.

Signed at Allegheny in the county of Allegheny, State of Pennsylvania, this tenth day of December, A. D. 1909.

EDWARD CHARLES HAWKINS.
